MASSAGING AND STIMULATING IMPLEMENT

Filed June 27, 1927

Dr. Hermann Krauter, INVENTOR
BY Victor J. Evans

ATTORNEY

UNITED STATES PATENT OFFICE.

HERMANN KRAUTER, OF PHILADELPHIA, PENNSYLVANIA.

MASSAGING AND STIMULATING IMPLEMENT.

Application filed June 27, 1927. Serial No. 201,713.

My invention relates to massaging and stimulating implements or devices and has particular relation to implements or devices for massaging the face, as described and 5 claimed for example in my co-pending application Serial No. 190,614, filed May 11, 1927.

The general object of my invention is to provide a novel massaging implement or device of the character indicated, which includes a hollow massaging and cream or lotion-applying bulb or head which is adapted to be filled with a heating or cooling medium for heating or cooling the same, as 15 may be desired in the use of the said implement or device.

Another object of my invention is to provide a novel massaging and stimulating device which includes a hollow massaging head 20 or bulb, the said device being provided with means for connecting the said head or bulb thereto, which means is adapted to permit the said head or bulb to be filled with a heating or cooling medium, as may be desired or necessary.

A further object of my invention is to provide a novel construction of means of the above character which comprises a cupping and massaging element, a vacuum-creating device for producing a condition of 30 vacuum in the said element, and which also includes a hollow massaging head or bulb adapted to be filled with a heating or cooling medium.

It also is an object of my invention to provide a novel implement or device for massaging and stimulating the skin which comprises a handle portion having a socket formed in a part thereof, the wall of which 35 socket is provided with openings, a hollow massaging head or bulb being adjustably connected in the said socket, whereby upon outward adjustment of the said head or bulb with respect to the said socket the said head 40 or bulb may be filled with a heating or cooling medium by immersing the said device in the said medium.

More specifically it is an object of my invention to provide a novel massaging and 50 stimulating device which comprises a tubular member, to one end of which member is connected means for producing a vacuum,

the other end of the said member being branched to provide a couple of laterally and oppositely extending members, the ends 55 of which are provided with sockets, a cupping and massaging element being connected in the socket of one of the said members and a hollow massaging and cream or lotion-applying member being connected in the 60 socket of the other of the said members, the said hollow massaging and cream or lotion-applying member being adapted to be filled with a heating or cooling medium.

Other advantages and objects from a practical standpoint will be pointed out in the description which follows or will become apparent from such description.

In order to readily understand the invention and the principle thereof, reference may 70 be had to the accompanying drawing, in which I have illustrated several forms of embodiment thereof. But it is to be understood that the invention is susceptible of being embodied in other forms of construction 75 than those shown and that changes in the details of construction may be made within the scope of the claims without departing from the principle of the said invention.

In the said drawing:

Fig. 1 is a view in vertical sectional elevation of a massaging implement or device embodying the invention in its preferred form;

Fig. 2 is a view similar to that shown in Fig. 1 but showing a modified construction embodying the invention;

Fig. 3 is a view similar to that shown in Fig. 2 but showing a modified construction of the implement or device shown in Fig. 2;

Fig. 4, which also is a view similar to that shown in Fig. 2, shows a modified construction of the implement or device shown in said Fig. 2; and

Fig. 5 is a view of the implement or device shown in Fig. 4, the said view being taken in a longitudinal plane extending through the line 5—5 of the said figure and at right angles to the plane in which the view shown in the said figure is taken.

Referring to Fig. 1 of the drawing, I have shown a device embodying the invention which comprises a bulb 1 preferably of

rubber, to which bulb the tubular member 2 is connected in known manner. The end of the tubular member 2 opposite the end to which the bulb 1 is attached is branched 5 to form a couple of laterally and oppositely extending members or branches 3 and 4. The member or branch 3, which is tubular, extends or may extend at practically a right angle with respect to the member 2, while 10 the solid member 4 extends or may extend at an angle slightly greater than a right angle with respect to the member 2, as shown, preferably intersecting the greater angle between the members 2 and 3. The 15 purpose of the angular relation of the members 2, 3 and 4 to each other will be pointed out hereinafter. But it will be understood that the various members or branches of the device may be arranged in such diverging 20 angular relation to each other as may be desired. These branches or members may be constructed of metal. The member or branch 3 is provided with a socket 5 in its outer end with which the nipple 6 formed 25 on the cup-shaped element 7 has screw-threaded engagement. This cup-shaped member or element consists of glass and may be described as a cupping element. A rubber gasket 8 is or may be inserted be- 30 tween the inner end of the nipple 6 and the bottom of the socket 5 to form a fluid-tight joint. The branch or member 4 also is provided with a socket 9 in its outer end with which the outer end portion of the tu- 35 bular stem 10 of the hollow bulb or head 11 has screw-threaded engagement, as shown. The wall of the socket 9 is provided with openings 12, which openings are located intermediate the ends of the said socket. 40 The bulb or head 11 consists of glass and has a relatively flat smooth surface formed thereon whereby the said head or bulb is adapted for applying massage cream or the like to the skin. By adjusting the said head 45 or bulb outwardly with respect to the socket 9 until the openings 12 are uncovered and then immersing the head or bulb 11 and the openings 12 in a liquid heating or cooling medium the latter will then flow through 50 said openings and thence into the said bulb. The said medium may be sealed or retained in the head or bulb by adjusting the latter inwardly with respect to the socket until the end thereof contacts with the gasket 14 pro- 55 vided on the bottom of the socket, as shown.

It will be observed that by reason of the fact that the interior of the cupping element 7 communicates through the nipple 6 and the branches 2 and 3 with the compressible 60 bulb 1, a vacuum may be created in the said element by depressing or collapsing the said bulb and subsequently releasing the same in known manner.

My novel massaging implement is particu- 65 larly intended to be employed in performing

a novel method of massaging and treating the skin invented by me. The use and operation of the said device and the performance of such method is as follows: The massaging head or bulb first is filled with a 70 suitable heating medium such as water or the like in order to impart heat thereto. Subsequently the said bulb is employed for applying a suitable massage cream or the like to the skin and for massaging the latter 75 with circular movements, the branches 2, 3 and 4 of the implement being employed as a handle for manipulating the said massaging head or bulb. As a result of such treatment the heat of the massaging bulb or head causes the cream or the like to become more or less fluid, thereby enabling the same to enter freely the pores of the skin, the latter being caused to open by the heat imparted 80 thereto by the said massaging head or bulb. As stated before, the cream or the like should be applied by working the bulb or head with a circular massaging movement, and when the skin is treated in such manner the foreign matter and the like which may be present therein or thereon become loosened from 85 the said skin. Subsequently the skin is subjected to the effect of vacuum and is massaged by placing the cupping element of the device in contact with the skin, creating a 90 vacuum therein by depressing and releasing the bulb 1, and manipulating the device with circular massaging movements. The vacuum which thus is created in the cupping element removes the cream or the like together 95 with foreign matter and the like which may be occluded thereby from the skin, thereby cleansing the latter, while the massaging treatment generally tends to increase the circulation of the blood and otherwise to 100 improve the condition of the skin.

From the foregoing it will become apparent that the cupping element and the massaging head or bulb are practically indispensable to each other in carrying out applicant's novel method of massaging and treating 105 the skin.

As will be understood, the bulb 11 may be filled with a cooling medium, such as cold water or ice, and when so filled may be employed for chilling or cooling the skin.

In Fig. 2 I have shown a modified construction of device embodying one feature of the invention. The said construction comprises a handle 15 having a socket 16 formed in the lower end thereof, the socket wall being provided with a plurality of openings 17 located intermediate the ends of the said socket. The tubular stem 10 of the hollow massaging head or bulb 11 has screw-threaded engagement with the socket 16, as is clearly shown in the said figure. The use and operation of this form of construction of the invention will be apparent from the foregoing description of Fig. 1.

The construction shown in Fig. 3 is identical with that shown in Fig. 2 except that the handle 15 extends at practically a right angle to the axis of the head or bulb 11 and 5 the stem thereof, as shown.

In Figs. 4 and 5 the handle 19, a portion only of which is shown, is provided with a collar 21, which collar and the exterior of the neck or stem portion of the bulb 11 are of 10 practically the same diameter. The said handle also is provided with a reduced extension 20 which terminates in a head 22 which serves to retain the rubber plug or sleeve on the said extension in contact with 15 the bottom side of the collar 21. The plug or sleeve 23 has openings or recesses of V-shape formed therein. Consequently when the plug or sleeve is partly withdrawn from the neck or stem of the bulb 11 the said bulb 20 may be filled with a liquid heating or cooling medium by dipping or immersing the device in the said medium. The collar 21 serves to limit the extent to which the sleeve 23 may be inserted into the neck of the 25 bulb 11.

It now will be seen that I have provided means of novel construction which may be employed for beautifying the skin and improving the condition thereof. A device 30 constructed according to my invention is efficient in use and may be manufactured economically.

Having thus described my invention, what I claim and desire to secure by Letters Patent is:

1. A massaging and stimulating device comprising a hollow bulb having a smooth surface formed thereon, a handle for the said bulb, the said handle being provided with a 40 socket, and means provided on the said bulb for adjustably engaging the said socket, the wall of the said socket being provided with an opening located intermediate the ends thereof, whereby when the said bulb is adjusted outwardly with respect to the said socket to uncover the said opening the said bulb may be filled with a heating or cooling medium by immersing the implement in the said medium.

50 2. A massaging and stimulating device comprising a tubular member, means connected to one end of said tubular member for producing a vacuum, the other end of the said member being branched to provide a 55 couple of laterally and oppositely extending branches, one of said branches being tubular, a cupping element connected to the outer end of said tubular branch, a hollow massaging bulb connected to the outer end of the other 60 of said branches, and means whereby when the said hollow massaging bulb is adjusted outwardly the said bulb may be filled with a heating or cooling liquid medium by immersing the same together with the connec-

tion thereof to the said other branch in the 65 said liquid medium.

3. A massaging and stimulating implement comprising a tubular member to one end of which is connected means for producing a vacuum, the other end of the said member being branched to provide a couple of laterally and oppositely extending branches, one of the said branches being tubular and having a cupping element connected thereto, the other of the said branches having a 70 socket formed therein, and a hollow massaging bulb adjustably connected in said socket, the wall of said socket having an opening formed therein whereby when the said bulb is adjusted outwardly with respect to the 75 said socket the said bulb may be filled with a heating or cooling liquid medium by immersing the same together with its connection to its supporting branch in said medium.

80 4. A massaging and stimulating device comprising a tubular member to one end of which is connected means for producing a vacuum, the other end of the said member being branched to provide a couple of laterally and oppositely extending branches, one of the said branches being tubular and having a socket provided therein, a cupping element connected in said socket, the other of the 85 said members being solid and provided with a socket, and a massaging device supported in said last named socket.

90 5. A massaging and stimulating device comprising a tubular member to one end of which is connected means for producing a vacuum, the other end of the said member being branched to provide a couple of laterally and oppositely extending branches, the ends of said branches having sockets formed therein, one of the said branches being tubular, a cupping element supported in the socket of the said tubular member, the wall of the socket formed in the other of the said branches having a plurality of openings 95 therein, and a massaging bulb mounted in said last named socket, the said bulb being adapted to be adjusted outwardly with respect to the said socket to uncover the said openings whereby the said bulb may be filled with a heating or cooling liquid medium by 100 immersing the device in the said medium.

115 6. A massaging and stimulating implement comprising a tubular stem one end of which is provided with a vacuum-producing means and the other of which is branched to provide a pair of laterally and oppositely extending branches, one of said branches being tubular and projecting at approximately a 120 right angle to the said stem and the other of the said branches projecting in an opposite direction and forming an obtuse angle with the first named branch, and a massaging device mounted upon the second named branch.

7. A massaging and stimulating device comprising a hollow bulb having a smooth surface formed thereon, a handle for said bulb, connecting means for said bulb and handle comprising a hollow shank formed on the bulb, and a member on the handle outwardly adjustable in relation to the shank, said connecting means having a port therein

which is opened by relative adjustment of the shank and member whereby the bulb may be filled with a heating or cooling medium by immersing the device in said medium while the bulb is connected to the handle. 10

In testimony whereof he affixes his signature.

DR. HERMANN KRAUTER.
